NECKTIE HOLDER

Filed Nov. 18, 1920

UNITED STATES PATENT OFFICE.

EDWARD JAMES NEITZEL, OF JERSEY CITY HEIGHTS, NEW JERSEY.

NECKTIE HOLDER.

Application filed November 18, 1920. Serial No. 424,920.

To all whom it may concern:

Be it known that I, EDWARD JAMES NEITZEL, a citizen of the United States, residing at Jersey City Heights, in the county of

5 Hudson and State of New Jersey, have invented certain new and useful Improvements in a Necktie Holder; and I do hereby declare the following to be a full, clear, and exact description of the invention, such as
10 will enable others skilled in the art to which it appertains to make and use the same.

This invention relates to a necktie holder, and the object is to provide a device of special construction for securing the flowing 15 end of a tie in position.

A further object is to provide a device having the form of a clasp pin, and including a member extending from one end of the bar of the pin and parallel with reference 20 thereto, for engagement with one of the overlapping elements of a shirt front.

A still further object is to provide a device serving the purpose specified, and one which may be formed from a single sheet 25 metal blank, the finished article including elements which correspond with the usual catch, pin, and spring held mounting means for the latter.

With the foregoing and other objects in 30 view, the invention consists in the novel construction of the device, as hereinafter more fully disclosed, and in the production of the blank from which the article is formed.

Figure 1 is a view in elevation of a portion 35 of a negligee shirt and necktie, illustrating the application of my improved holder, the holder being shown in dotted lines.

Figure 2 is a sectional view taken on the plane indicated by the line 2-2 of Figure 40 1, looking in the direction indicated by the arrows.

Figure 3 is a sectional view taken on a plane extending longitudinally and centrally through the neck tie holder.

45 Figure 4 is a view in rear elevation of the necktie holder.

Figure 5 is a plan view of the blank from which the neck tie holder is made, and

50 Figure 6 is a section on the plane indicated by the line 6-6 of Figure 4 looking in the direction indicated by the arrows.

The blank from which the device is formed includes a strip of suitable metal, the principal portion of which is of uniform width, one end however being of reduced 55 width, and slightly tapering, as shown, to form the pin per se. The wider portion of the blank is slotted at the point indicated, the metal being upset to form a catch for retaining the end of the pin. 60

The intermediate section of the blank corresponds with the element usually termed the bar, and is designated 10, and formed therewith is the clasp 12 having substantially the same width as the bar, although 65 the exact dimensions, are not important. The extreme or free end of the wider portion is rounded, as shown and the blank is bent upon itself at 15, forming the connecting element between the clasp 14 and the 70 bar 10.

The pin 16 is formed by cutting away the metal of the original blank, to form a tapered element having a point 17, and merging into that portion of the article constituting 75 the bar. At the point of juncture, shoulders 18 are formed, the metal being bent upon itself at 19 and forming at this point an element corresponding with the usual spring hinge mounting of the pin. 80

The catch 21 is formed by upsetting a portion of the metal of the blank, the upset portion being deflected in two directions, and serving to properly retain the pin.

In the use of the device the pin is passed 85 through the under side of the flowing end of the tie and is secured by the catch. The clasp is then slipped over the adjacent edge portion of the shirt front, or bosom, and owing to the resiliency of the metal, a 90 sufficiently secure connection is effected for holding the tie in correct position, and yet permitting immediate detachment when desired. When in position, the device does not show on the front of the tie. 95

Having thus described the invention, what I claim is:—

A tie holder consisting of a blank provided with a portion struck out to form a catch, a clasp extending from and returned 100 toward the holder on the opposite side to the catch, the blank being reduced to form

a pin, said pin being returned from the entrance to the clasp across the opposite face of the blank to engage the catch, the blank having shoulders at the junction of the pin and the remainder of the blank beyond the entrance to the clasp and offset with relation to the last mentioned face, the holder thus being substantially S-shaped and

adapted for connection to a tie and shirt and concealed by the tie.

In testimony whereof I affix my signature in presence of two witnesses.

EDWARD JAMES NEITZEL.
